UNITED STATES PATENT OFFICE.

EDWARD W. McINTYRE, OF CLEVELAND, OHIO, ASSIGNOR TO HADLEY F. FREEMAN,
OF LAKWOOD, OHIO.

LAMP SOCKET.

Application filed July 14, 1923. Serial No. 651,556.

To all whom it may concern:

Be it known that I, EDWARD W. McINTYRE, a citizen of the United States, residing at Cleveland, in the county of Cuyahoga and State of Ohio, have invented a certain new and useful Improvement in Lamp Sockets, of which the following is a full, clear, and exact description; reference being had to the accompanying drawings.

10 Until recently, except for certain types of ornamental installation of extremely restricted applicability, because of the low efficiency of the incandescent lamp compared to that of the arc lamp and because 65
15 of an inability to produce reliable incandescent units of suitable size, it has been impractical to utilize incandescent lamps for the general illumination of streets. The development of the gas filled tungsten 70
20 lamp, however, has provided an incandescent lamp having an efficiency comparable with that of the arc lamp and of a type which can be produced in units of a magnitude equaling or surpassing that in 75
25 which arc lamps are customarily produced. Accordingly, the perfection of the gas filled tungsten lamp has provided an incandescent lamp which is suitable for general street lighting and which has come into wide- 80
30 spread use for that purpose.

In developing units of this type suitable for street lighting the existing style of lamp base and socket was retained without modification as to form. The lamp socket 85
35 thus retained comprised essentially a base of suitable insulating material, such as porcelain, which carried a shell screw-threaded to engage cooperating screw threads carried by the lamp base and a center contact mounted to engage the center contact of the lamp base. This socket center contact was usually resiliently supported from the socket base in order to improve the contact between itself and the center contact of the lamp base and to impart to the lamp a tendency to move outward which improved the contact between 90
40 the lamp base and the shell.

In lamps of the type described the lamp 95
50 base, during a long continued operation, reaches a relatively high temperature which is readily communicated to the adjacent parts of the socket and apparently is effective to remove the resiliency from the center socket and produces an imperfect

contact between the lamp and the socket and particularly between the center contact of the lamp and the center contact of the socket. In an installation wherein the lamps are arranged in parallel this imperfect contact between the center lamp contact and the center socket contact results only in a slow deterioration of the contacts which usually does not destroy the socket contact for an appreciable time but in those installations wherein the lamps are connected in series such an imperfect contact concentrates at that point a large part of the total voltage of the series and rapidly destroys the two contacts perhaps throwing the entire 60
65 series of lamps out of action and in any event necessitating the renewal of both the lamp and the socket.

In addition, the action of the resilient center socket contact, and perhaps of other 75 forces, is effective in many cases to displace the lamp in the socket during vibration of the lamp and socket such as is caused by the passing of heavy vehicles.

So far as I am aware, in spite of many 80 attempts, there has been devised heretofore no socket which satisfactorily overcame these difficulties. My invention, however, has produced a socket having a center contact so formed, supported, and connected, as 85 to maintain firm contact with the center lamp contact and a shell so formed as to retain the lamp against vibratory displacement and accordingly my invention has produced a socket which avoids the defects 90 existing in sockets theretofore produced. In the drawings accompanying this specification and forming a part thereof I have shown, for purposes of illustration, one form which my invention may assume. In 95 these drawings:

Figure 1 is an elevation of this illustrative form of my invention,

Figure 2 is a plan view of the socket 100 shown in Figure 1, while

Figure 3 is a section on the line 3-3 of Figure 2.

The socket herein disclosed omits certain parts not essential to the understanding of my invention. This socket, however, comprises a socket base 11 which may be of any suitable material such as porcelain and carries, by means of two bolts 12 passing upwardly through the socket base 11, a conducting member 13 provided with a suitable 105
110

terminal 14 and overlying the flange 15 of the shell 16 to hold the shell 16 securely in position upon the socket base 11 and electrically connected to the terminal 14. The 5 socket base 11 also carries, by means of a bolt 18, a second terminal 19 which clamps between itself and the socket base 11 one end of a flexible conductor 20 the other end of which encircles a stem 21 depending from 10 a center socket contact 22, reciprocable within a longitudinal aperture 23 within the socket base 11, biased outwardly by means of a helical spring 24 coiled thereabout and compressed between the shoulder 25 of the 15 socket base 11 and a washer 26 which encircles the stem 21 below the conductor 20, and limited in its outward movement by means of a head 27 formed at its lower end and arranged to engage an annular shoulder 20 28 on the socket base 11.

The shell 16 is herein shown as provided with the usual screw threads 17 arranged to engage cooperating screw threads carried by the lamp base and with means to prevent 25 vibratory displacement of the lamp from the socket which means is herein shown as comprising a wire 29 wound spirally about the exterior of the shell 16, having its ends secured to lugs 30 stamped from the shell 30 16, and projecting through apertures 31 in the shell 16 into strong frictional engagement with the lamp base and acting thereby to prevent vibratory displacement of the lamp base. It will be obvious that other 35 means may be employed for this purpose but I prefer to employ the means herein disclosed.

It will be obvious from the above description that in the construction herein shown 40 the center socket contact is supported independently of the conductor connecting it with its terminal, in a manner which permits the use of a biasing spring independent of the connecting conductor, and in such 45 way that the spring pressure acts to effect movement directly longitudinal of the socket and the lamp and not at an angle thereto as in the sockets now commonly employed, and that the construction herein shown there- 50 fore supports the center socket contact in such manner that it maintains constant engagement with the center lamp contact and thus avoids the defects existing in the sockets now generally in use. It will also be 55 obvious from the within description that the construction herein disclosed also provides means to prevent vibratory displacement of the lamp by the spring 24 or otherwise.

The embodiment of my invention herein disclosed has been developed particularly 60 for use for incandescent street lighting and is disclosed as so used. It will be obvious to those skilled in the art, however, that it may be used otherwise and it will be understood that I contemplate the use of my invention wherever it is applicable. It will 65 also be obvious to those skilled in the art that the particular embodiment of my invention herein disclosed may be variously modified without sacrificing the advantages 70 or departing from the spirit of my invention and accordingly that this entire disclosure is illustrative only and that my invention is not limited thereto.

I claim:

1. An electric lamp socket comprising a base having circuit terminals thereon, carrying a screw threaded socket adapted to receive the base of a lamp, provided with a longitudinal aperture therein, and having a center contact structure comprising a stem 80 slidable in said aperture, a head on said stem arranged to engage the center contact of the lamp, spring means acting to force said head against said center contact of the lamp, 85 and a conductor connected to one of said terminals and interposed between said spring means and said head and held by said spring means in electrical communication with said head.

2. An electric lamp socket comprising a base provided with a longitudinal aperture, a center contact provided with a depending stem slidable in said aperture, a terminal 95 for said contact, a conductor connected to said terminal and surrounding said stem beneath said contact, a washer surrounding said stem below said conductor, and a helical spring encircling said stem and acting against said washer to force said conductor against said contact and to tend to move said contact outwardly.

3. An electric lamp socket comprising a base provided with a longitudinal aperture, a center contact provided with a depending 105 stem slidable in said aperture, a terminal for said contact, a conductor connected to said terminal and surrounding said stem beneath said contact, a washer surrounding said stem beneath said conductor, and a spring acting 110 against said washer to force said conductor against said contact and to tend to move said contact outwardly.

In testimony whereof, I hereunto affix my signature.

EDWARD W. McINTYRE.
